UNITED STATES PATENT OFFICE.

MARCUS C. STEARNS, OF BUFFALO, NEW YORK.

AERIAL WEAPON.

1,309,156.

Specification of Letters Patent.

Patented July 8, 1919.

Application filed May 18, 1918. Serial No. 235,382.

To all whom it may concern:

Be it known that I, MARCUS C. STEARNS, a citizen of the United States, residing in the city of Buffalo, county of Erie, in the State of New York, have invented certain new and useful Improvements in Aerial Weapons, of which the following is a specification, reference being had to the accompanying drawings, forming a part hereof.

- 10 This invention has for its object the production of a weapon to be dropped from an airship or aeroplane in the midst of a group of the enemy to kill and wound without the use of an explosive. The projectiles, 15 whether slugs, darts or bullets, are discharged when the weapon reaches the ground by the centrifugal action developed through the very high velocity of rotation about a vertical axis acquired in the fall of 20 the weapon from a great height. The invention will be more fully explained hereinafter with reference to the accompanying drawings in which it is illustrated in several different embodiments and in which— 25 Figure 1 is a view in elevation, partly in vertical section, of one form of the new weapon, with the parts in the relative positions which they occupy when the weapon is released from an airship or aeroplane.

30 Fig. 2 is a similar view, showing the parts in the relative positions which they assume when the weapon strikes the ground.

Fig. 3 is a view of the same in horizontal section on the plane indicated by the line 35 3—3 of Fig. 1, looking in the direction of the arrows.

Fig. 4 is a view similar to Figs. 1 and 2, but showing a slightly modified embodiment.

40 Figs. 5 and 6 are detail views, on a larger scale, respectively in vertical section and in horizontal section on the plane indicated by the line 6—6 of Fig. 5, illustrating the application of a timing device to release the projectile containers instead of the impact device shown in Figs. 1—4.

Figs. 7 and 8 are detail views illustrating other devices for releasing the projectile containers.

50 The operation of the weapon depends upon the centrifugal action due to the great velocity of rotation developed in the fall of the weapon from a great height and the weapon is therefore provided with suitable vanes by which the rotation of the weapon is assured as it falls, and with projectile

containers which are permitted to release their contents so that such contents shall be discharged by centrifugal action at the proper time. In one embodiment of the invention provision is made for the release of the projectile containers and the discharge of their contents when the weapon strikes the ground, and in other embodiments provisions are made for the release of the projectile containers and the discharge of their contents at a predetermined time or when predetermined conditions have been established.

55 In the embodiment of the invention illustrated in Figs. 1, 2 and 3, the weapon comprises a central stem or spindle *a* which is preferably tubular to receive the axially movable releasing device or stem *b*, a hub *c*, secured to the upper end of the spindle *a* and carrying the vanes *d*, and segmental containers *e* for the projectiles employed, which may be bullets, or slugs, or darts, or projectiles of any preferred character. The releasing device or 60 stem *b* has a wire cutting head *b*¹ and a foot *b*². The hub *c* is preferably hollow and arranged to contain an exploding charge *c*¹ provided with a detonator *c*² so that the weapon shall be destroyed when it has 65 fulfilled its purpose. Each container *e* is pivotally hung at its upper end, as at *e*¹, upon the spindle *a* and may be constructed of any suitable material, such as thin sheet metal. It is preferably larger at the lower end 70 than at the upper end and is provided at its lower end with a hinged door *e*² which is lightly engaged by a lip *e*³, so that when the container is released and flies into a horizontal position under the influence of the 75 centrifugal action, the door *e*² is released at the same time to permit the discharge of the mass of projectiles within the container. The containers are shown as held in normal 80 position by cross wires *f* which are severed by the wire cutter *b*¹ when the weapon strikes the ground. When this takes place, the weapon being then in a state of rotation at a very high velocity about its own vertical axis, through the action of the air 85 through which it falls upon the vanes *d*, the projectile containers *e* fly out immediately to horizontal positions, the doors open at the same time, and the projectiles are discharged with great force, sufficient to 90 wound those of the enemy who may be standing about the spot on which the

weapon falls. As the body of the weapon continues its descent, after the foot of the releasing device has struck the ground, the head b' of the releasing device makes contact with the detonator c^2 and brings about the explosion of the charge c' within the hub c and the destruction of the weapon.

In the embodiment of the invention shown in Fig. 4 the construction is substantially the same as that already described except that each container e is hinged to the spindle a at the lower end of the container, as at e^4 , and the door e^5 is hinged to the bottom of the container, as at e^6 . The retaining wires f' in this instance are arranged to coöperate with the small upper ends of the containers. In this arrangement of the containers, the weight of each container and its charge assists in its movement to a horizontal position when released. In other respects, the operation of the weapon as shown in Fig. 4 is the same as that already described with respect to Figs. 1, 2 and 3.

In the embodiment of the invention illustrated in Figs. 5 and 6 a timing device is applied to the weapon to release the containers e at the predetermined time. The containers are hingedly mounted upon the tubular standard or spindle a' at their lower ends and are held in normal position by pins f^2 , notched, as at f^3 within the standard a' for engagement with vertical pins g actuated upon by lifting springs g' . The pins g are guided in a plate c^{21} of the hub c^3 which supports the vanes d and are held down normally by a plate h provided with holes h' which are brought into registration with the pins g at the proper time by a timing device, indicated generally at h^2 . Such timing device may be of any suitable character and need not be shown or described in detail. A timing device adaptable for the purpose is shown in U. S. Patent of Schneider, No. 969,497, September 6, 1910. The hub c^3 is held to the standard a' by a shearable pin a^2 and the upper end of the standard a' is provided with firing pins a^3 in alinement with detonators c^4 which communicate through suitable flash passages with the explosive charge c' within the hub. In the operation of this form of the weapon, the projectile containers are released and discharge the projectiles at the predetermined time, before the weapon has reached the ground. In its continued fall the lower end of the standard a' strikes the ground, the pin a^2 is sheared, the hub deformed and the ignition of the explosive charge is effected through contact of the firing pins a^3 with the detonators c^4 so that the weapon is destroyed.

In the embodiment of the invention shown in Fig. 7 the lower end of the standard a^4 receives a charge of compressed air in a chamber a^5 which communicates through a

valve a^6 with a chamber a^7 in which is mounted a piston a^8 which is armed with a wire cutter a^9 . The valve is pressed from its seat at the proper time by a pin k which is acted upon by a cam h^3 on a disk h^4 driven by a timing device h^2 of any suitable construction. When the timing device acts upon the pin k to open the valve a^6 , the piston a^8 is driven upward so as to cause the cutter a^9 to sever the wires f^4 and release the containers e which are mounted upon the standard substantially as shown in Fig. 4. The projectiles are then discharged and in the continued falling of the weapon the hub is exploded as already described with reference to Fig. 5, through contact of the firing pins a^3 with the detonators c^4 .

Still another means for effecting the release of the containers at a predetermined time or when predetermined conditions are fulfilled is shown in Fig. 8. The spindle or standard a^{10} carries at its upper end the chambered hub c^5 with wings d and has the containers e hinged thereon and held in normal position by a wire f^5 as before. On top of the hub c^5 is mounted an ordinary centrifugal governor m . The lower member m' of the governor is mounted so as to rotate freely with respect to the hub c^5 and the upper member m^2 is pressed upward normally by a spring m^3 . The upper member m^2 has secured thereto vanes m^4 set in vertical planes and carries adjustably (by means of a nut m^6) a releasing rod m^7 which is adapted to act on the wire f^5 . When the weapon begins to fall it begins to rotate slowly, the governor also rotating slowly with the rest of the weapon. As the velocity of the fall increases, the velocity of rotation of the weapon, including the governor, also increases and the governor acts in the usual manner to pull down the upper member m^2 and the rod m^7 , the lower member being held from rising by a flange m^8 . When the predetermined speed of rotation is attained the rod m^7 will have been forced down far enough to sever the retaining wires f^5 so as to release the containers. In order to retard somewhat the action of the governor, the upper member m^2 is equipped with the vertical vanes m^4 and these vanes may be more or less inclined from the vertical so as to regulate the retarding action to suit different conditions of use. By means of the adjustment of the nut m^6 on the rod m^7 the time of action of the rod on the retaining wires can be advanced or delayed.

Various other embodiments of the invention will suggest themselves and it is to be understood that, except so far as pointed out in the claims, the invention is not restricted to any of the particular constructions shown and described herein.

I claim as my invention:

1. An aerial weapon comprising a stand-

ard, means to set up rotation of the standard as the weapon falls, a projectile container hinged on the standard, means to rotate the standard in normal position and means to

5 release the container to permit it to assume a horizontal position and discharge its projectiles under the influence of centrifugal action.

2. An aerial weapon comprising a standard, means to set up rotation of the standard as the weapon falls, a projectile container mounted on the standard, means to retain the container in normal position, means to release the container to permit it to assume a horizontal position and discharge its projectiles under the influence of centrifugal action, and means to determine the time of action of the releasing means.

3. An aerial weapon comprising a standard, vanes carried by the standard to set up rotation thereof as the weapon falls, a plurality of projectile containers hinged on the standard, means to retain said containers normally in substantial parallelism with the

standard and means to release the containers 25 to permit them to discharge their projectiles under the influence of centrifugal action.

4. An aerial weapon comprising a standard, vanes carried by the standard to set up 30 rotation thereof as the weapon falls, a plurality of projectile containers hinged on the standard, retaining wires to hold the retainers normally in parallelism with the standard and means to sever the retaining 35 wires.

5. An aerial weapon comprising a standard, vanes carried by the standard to set up rotation thereof as the weapon falls, a plurality of projectile containers hinged on the 40 standard, retaining wires to hold the containers normally in parallelism with the standard, means to sever the retaining wires and devices to determine the time of operation of such last named means. 45

This specification signed the 15th day of May, A. D. 1918.

MARCUS C. STEARNS.
